UNITED STATES PATENT OFFICE.

JOHN EDGAR FEIOCK, OF MARTINS FERRY, OHIO, ASSIGNOR TO EMIL NORTEMAN, OF WHEELING, WEST VIRGINIA.

CABLE-HANGER.

No. 927,032.

Specification of Letters Patent.

Patented July 6, 1909.

Application filed July 7, 1908. Serial No. 442,286.

To all whom it may concern:

Be it known that I, JOHN EDGAR FEIOCK, a citizen of the United States of America, and resident of Martins Ferry, county of 5 Belmont, and State of Ohio, have invented certain new and useful Improvements in Cable-Hangers, of which the following is a specification.

This invention relates to cable-hangers, 10 and more particularly to that class of clips or hangers employed for supporting electric cables from messenger wires; and it has for its primary object to provide an extremely simple, inexpensive, durable and efficient 15 hanger which may be quickly and conveniently applied and which may be readily removed when occasion requires.

A further object is to provide a device of the character mentioned the formation of 20 whose interlocking ends is readily accomplished without the employment of complicated or expensive forming instruments or tools.

In describing the invention, reference is 25 herein had to the accompanying drawing, forming a part of this specification, in which—

Figure 1 is a perspective view of the invention, illustrating the application thereof; 30 Fig. 2 is a side elevation of the same; Fig. 3 is a detail perspective view illustrating the wire members detached; and Fig. 4 is a central longitudinal sectional view of the opposite ends of the device, disconnected.

Referring to said drawing, in which like reference characters designate like parts throughout the several views—1 indicates a strap, formed of thin flexible sheet metal, adapted to be bent into substantially the 40 form of the letter S, with the lower loop 1^a thereof relatively larger than the upper loop 1^b, the first mentioned loop being designed to embrace the cable 2, while the last mentioned loop embraces the messenger wire 3. One terminal of said strap is looped or folded, as shown at 4, over the transversely-extending body 5^a of a wire member 5 which is loosely held by said strap so as to be freely movable. Said member 50 comprises said body 5^a, a pair of parallel arms 5^b and outwardly-directed terminal loops 5^c, the latter forming eyes for the reception of hooks 6^a forming a part of a wire member 6 which is similar to the member 5 in every respect except that the hooks of

the former take the place of the terminal loops of the latter. Said member 6 is held in the opposite terminal of said strap, said terminal being looped over the transversely-extending body 6^b of the member, as shown 60 at 7. Both wire members 5 and 6 are preferably held loosely by said strap so that they may be swung or turned with relation to each other to facilitate the engagement of their terminals.

In applying the device, one end of the strap is bent into loop shape and is slipped up over the cable so as to closely embrace the latter; then the opposite end of said strap is passed up under, behind, and over 70 the messenger wire; then, holding the arms of the member 5 with the thumb and a finger of one hand and the arms of the member 6 with the thumb and a finger of the other hand so as to cause the arms of the two 75 members to lie substantially in alinement, the terminal ends of the strap are drawn together and the hooks 6^a are inserted in the eyes 5^c. As is obvious, the weight of the cable serves to retain the hooks in engagement with said eyes, and accidental displacement is thus rendered impossible.

Rivets 8 are preferably employed for securing the looped-over ends 4 and 7 of the strap to the body thereof.

Having thus described my invention, wha- 85 I claim as new, and desire to secure by Letters Patent, is—

1. A cable hanger comprising a substan- 90 tially S-shaped strap, a wire member having a transverse body portion held in each end of said strap, both of said members having parallel arms, the arms of one member terminating in hooks and the arms of the opposite member terminating in eyes adapted for the 95 reception of said hooks both of said members being free to swing with relation to the strap and to each other to facilitate the insertion of the hooks of the one within the eyes of the other.

2. The combination with a cable and a messenger wire, of a strap one end of which is bent to closely embrace the cable and the other end of which is bent in a direction opposite to that of the first mentioned end to 105 engage the messenger wire, wire members held by and freely movable in the opposite ends of said strap, each wire member consisting of a transverse body portion engaged by said strap and a pair of parallel arms, hooks form- 110

ing the terminals of the arms of one member, and loops forming the terminals of the arms of the other member, said loops being adapted for the reception of said hooks said members being pivotally held by said strap so as to enable the hooks and the eyes to freely approach each other.

In testimony whereof I affix my signature in presence of two subscribing witnesses:

JOHN EDGAR FEIOCK.
